Specification of Letters Patent.

Patented Sept. 7, 1920.

Application filed August 11, 1916. Serial No. 114,233.

To all whom it may concern:

Be it known that I, DONALD NOBLE, a citizen of the United States, residing at Bridgeport, in the county of Fairfield and

5 State of Connecticut, have invented certain new and useful Improvements in Sewing-Machines, of which the following is a specification, reference being had therein to the accompanying drawings.

10 This invention relates to improvements in blind-stitch sewing machines and has to do more particularly with the providing of an improved feeding-mechanism adapted to the requirements of a comparatively large 15 variety of products. Prior to the devising of the present improved means machines of the present character have been constructed special to the requirements of a comparatively small range of application due to the 20 distinctly unlike conditions of seam-formation demanded by the differences in effect which the seaming operations must have on the product.

When blind-stitching the stiffenings comprising hair-cloth, buckram, crinoline or other stiffening materials to the fabric comprising the lapels of coats, cloaks and other outer garments, the stitching operation must give to the fabrics a natural roll which needs 25 only to be pressed to give to it its proper form, while in the seaming of the bottoms of trousers, felling, taping of coats and many other stitching operations there must be no tendency of the superposed plies to 30 change their form or relationship owing to 35 the stitching operation.

In the accompanying drawings, which form a part of the specification, Figure 1 is a plan view of a blind-stitch sewing machine 40 employing the invention, the frame-plate being omitted to bring to view the feed and feed-lift levers of the upper feeding-mechanism. Fig. 2 is a view in side elevation, at the right of the operator, of Fig. 1 except 45 that it includes the frame-plate and sectional views of the front and back feed-frame face-plates, a portion of the oscillating frame being also shown in section. Fig. 3 is a view in side elevation, at the left of 50 the operator, of Fig. 1, except that it includes the frame-plate and illustrates the gear-covering plate in section. Fig. 4 is a view in rear end elevation of Fig. 1, the machine frame being shown in section to 55 bring to view certain elements later to be re-

ferred to. Fig. 5 is a view in front end elevation of Fig. 1, together with the frame-plate, the gear covering plate being shown in section and the front feed frame plate broken away at its opposite ends to better illustrate 60 the lower feed-dog actuating mechanism. Fig. 6 is an under side view of Fig. 1. Fig. 7 is a view, in perspective, of the upper feeding-mechanism. Figs. 8, 9, 10 and 11 are views, each of which include the feed-frame, 65 feed-dog, feed-connection and feed-dog actuating cams, the respective views illustrating, in sequence, the four-motions of the feed-dog. Fig. 12 is a view of the cloth-presser detached from the machine to better 70 illustrate the needle-loop guard. Figs. 13 and 14 are views, partly in full lines and partly in section, of the feed reversing mechanism illustrating the elements in the positions which they occupy when feeding 75 the fabric to the left of the operator and in a reverse direction, respectively. Fig. 15 are detailed views, in perspective, of certain of the elements shown in section in Figs. 13 and 14. Figs. 16, 17 and 18 are views in 80 front end, plan and side elevation, respectively, of the means employed for annulling the effective action of the upper feeding-mechanism when, for any purpose, it is desired to effect an endless seam comprising 85 oppositely directed lines of seam formation, as will later be explained.

Referring to the figures, 1 represents the sewing machine frame in which is journaled in suitable bearings the main-shaft 2 carrying at one end the belt-pulley 3 and at its opposite end the shaft-flange 4. 5 denotes an oscillating cylinder carried by a rock-shaft 6 journaled in a suitable bearing formed in said frame and suitably held 90 against endwise movement. Mounted in a suitable bearing formed in the cylinder 5 is a needle-carrying bar 7 provided with a needle holding bracket 8 carrying a needle 9, the latter coöperating with an oscillating 100 loop-taker 10, provided with a thread-bobbin 11, to form stitches, said loop-taker being carried by a spirally grooved oscillating shaft 12 suitably journaled in said oscillating cylinder. Into the shaft-flange 4 is suitably secured a crank-pin 13 upon which is pivoted one end of a two-part needle-bar actuating connection 14 whose opposite end is pivotally connected with a reciprocating cross-head 15 suitably secured at one end 110

to the needle-bar, its opposite end being provided with an internally formed spiral thread (not shown) meshing with said spiral grooves, thus transmitting, through the reciprocal movements of said cross-head stitch-forming movements to said oscillating shaft and needle-bar.

In the formation of a blind-stitch seam, as effected by the present construction, the 10 needle passes alternately through and outside of the fabric, and when piercing the fabric enters and emerges from the same side of the latter, and this is accomplished by giving to the cylinder 5 a rocking movement, as will now be explained.

Upon the main-shaft 2 is suitably secured a gear member 16 which meshes with a gear member 17 carried by a feed actuating shaft 18, and as said gears are of the ratio of two 20 to one the shaft 18 is given one rotation to two of the shaft 2, the end of the shaft 18 opposite to that carrying the gear 17, being provided with a reduced concentric extension 19 carrying a double and symmetrical 25 eccentric 20, which latter engages the oppositely arranged walls, as 21, of the forked end 22 of the oscillating frame 5, to give to the latter its oscillatory movements to alternately place stitches in and out of the fabric.

20 23 represents the prime gear member of a train of gears connecting the main-shaft with the feed-shaft 24, the gear member 25 acting as an idler for connecting the gear member 23 with the like gear member 26 35 fast on the feed reversing shaft 27 journaled in an arm 28 of the rocking feed-frame 29, the latter being held in operative relationship with its coating elements by the flange 30 of said arm 28 contacting with 40 the end wall 31 of the bearing 30' and the securing of the rocking frame lever 31' by screw 32 against the oppositely arranged wall 33 of said bearing. The end of the shaft 27, opposite that carrying the gear member 26, is provided with an enlarged 45 bearing surface 34 provided with a slot 35 and head 36, and onto said enlarged portion are mounted the bevel-gears 37 and 38 to turn with the shaft 27 as driving or 50 driven elements as the operator may will, the gears 37 and 38 being held in engagement with a like bevel-gear 39, carried by the feed-shaft 24, by the head 36 of said enlarged portion and the boss 40 of the machine frame, respectively.

To transmit from the shaft 27 rotary movements to the shaft 24 in directions clockwise or contra-clockwise, the enlarged portion 34 of the shaft 27 is provided with a 60 tubular opening 41 against the bottom wall 42 of which is seated a spring 43, and upon said enlarged portion is slidably mounted a switch-collar 44 provided with dog-pins 45 and 46, and into a groove 47 in said collar 65 is secured by screw 48 a follower 49 track-

ing the slot 35, said follower being provided with a spring-step 50 manually controlled to transmit to the shaft 24 rotary movements in opposite directions by forcing the plunger 51 inward by the action of the bellcrank-lever 52 or by permitting the spring 43 to move the collar 44 in an opposite direction, as will now be more fully explained.

In Fig. 13, the feed reversing elements are shown as when transmitting from the shaft 27 clockwise movements to the shaft 24, such power transmission being effected by the operator permitting the spring 43 to move the dog-pin 45, carried by the switch-collar 44, into engagement with the opening 53 in the gear 37, thus causing the latter to drive the gear 39, but when it is desired to reverse the action of the shaft 24 and cause the feed movements of the fabric to be reversed the operator, through a suitable treadle (not shown) and treadle connection 54, rocks the bellcrank-lever 52 on its fulcrum 55 sufficient to bring the free end 56 of the lever 52 in contact with the surface 57 of the rocking frame 29, thus causing the dog-pin 46 to, in 90 opposition to the resiliency of the spring 43, engage the opening 58 in the gear 38 and operatively connect the latter with the gear 39, the gear member 37 idly turning on the shaft 27. The purpose of bringing the free 95 end 56 of the bellcrank-lever in contact with the surface 57 of the rocking frame 29, is to minimize the friction which otherwise might result from the plunger 51 contacting the spring-step 50 of the follower 49, and the 100 opposite end of said plunger with the end of the screw 58' adjustably secured in said bellcrank-lever.

The vertically movable frame for housing the feed-dog and means for giving to the latter its four motions, comprises supports 59 and 60 carrying at their upper ends a throat- or needle-plate 61 secured by screws, as 62, the opposite ends of said supports being secured by screws, as 63, to a tie-plate 64, the front and rear sides of said frame being provided with face-plates 65 and 66, respectively, secured by suitable screws (not shown) threaded into the openings, as 67. 68 and 69 represent the feed and feed-lift double eccentrics, respectively, carried by the feed-shaft 24 and arranged one at one side and the other at the opposite side of the tie-plate 64 into which the forward end of said feed-shaft is journaled. 70 denotes the feed-dog rigidly secured upon the upper ends of the feed-dog carrying rods 71 and 72, the opposite ends of the latter being rigidly secured in the feed-lift bracket 73 provided with the forked opening 74 into which tracks the feed-lift eccentric 69. 75 denotes a feed yoke slidably mounted upon the rods 71 and 72 and on the front side of said yoke is pivoted the upper end of a feed actuating lever 76, the opposite end of the 130

latter being forked to receive the feed eccentric 68, said feed actuating lever being provided with a bearing-stud 77 journaled in a suitable opening 78 in the face-plate 65.

Supposing the feed-dog and the elements for controlling its four motions to occupy their positions as illustrated in Fig. 8, with the feed-dog at its limit of downward movement and in its retracted position ready to be moved upward into engagement with the fabric, the first 90° of rotation of the feed-shaft 24 would cause the cam-portion *a* of the feed-lift eccentric 69 to act upon the wall *b* of the bracket 73 to, in opposition to the resiliency of the springs 79, elevate the feed-dog to its limit of upward stroke, as in Fig. 9, and during such time the concentric portions *c* and *d* of the feed eccentric 68 act upon the walls *e* and *f* of the feed actuating lever to hold the latter against rocking movement on its pivot 77. In the second 90° movement of the feed-shaft 24 the eccentric portions *g* and *h* of the feed-eccentric 68 act on the walls *e* and *f*, respectively, of the forked opening 76' to rock the lever 76 in the direction indicated by the arrow *S*, Fig. 9, and simultaneous with such movement of the lever 76 the eccentric portions *a* and *i* of the feed-lift eccentric 69 will act on the walls *j* and *k* of the forked opening 74 in the bracket 73 to give to the feed-dog its feed movement. In the third 90° movement of the shaft 24 the eccentric portion *i* of the eccentric 69 acts upon the wall *b* of the bracket 73 to permit the springs 79 to move the feed-dog to its lowest position, during which time the eccentric 68 holds the downward movement of the feed-dog to a right line, leaving the elements as illustrated in Fig. 10, when the eccentric portions *g* and *h* of the eccentric 68, and like eccentric portions *a* and *i* of the eccentric 69 act on the walls *e* and *f* and *j* and *k*, respectively, to move the feed-dog in a right line to its first position, as illustrated in Fig. 8, thus giving to the feed-dog rectangular movements whose oppositely arranged movements are of like amplitude.

80 represents the feed-frame guiding bracket provided with a shank 81 secured by screw 82 in an opening 83 in the frame 1, said bracket being provided with transversely arranged arms 84 and 85 which embrace the vertically movable feed-frame, and into the free ends of each of said arms is threaded a teated screw 86 and 87, respectively, the teat of screw 86 tracking a slot 88 formed in the face-plate 65 and the teat of the screw 87 tracking a like slot 89 in the face-plate 66. The purpose of the bracket just described is to secure the vertically movable feed frame against movement about the axis of the shaft 24.

In the present, as in the construction represented by U. S. Patent No. 1,133,572, March 30, 1915, to the same inventor and to which

construction the present invention is applied, the under feeding-mechanism must be capable of being moved downward to accommodate the inserting of the fabric below the cloth-presser and to effect this, the rocking frame lever 31' secured at one end by screw 32 to the arm 28 of the rocking frame 29 is, at its opposite end, acted on by a roller 90 carried by a stud 91 suitably secured in a treadle actuated bracket 92 fast on a rock-shaft 93 journaled in suitable bearings formed in the frame 1, and through the opening 94 in said bracket extends a treadle-rod 95 connected with a second suitable treadle (not shown), said rod being provided with an adjustably secured collar 96 provided with a crosshead 97, which latter in its upward movements rocks the lever 31' in opposition to the resiliency of the spring 98, and through the connections pointed out move downward the vertically movable frame carrying the under feeding-mechanism. The spring 98 is mounted upon a rod 99 suitably secured at its lower end in a rocking stud 100 carried by the lever 31', the upper end of said rod passing through a tubular bushing 101 threaded into the frame and threaded to receive the adjusting nut 102 against the lower end of which said spring abuts, said nut being provided with an upwardly extended slightly tapered threaded portion 103 provided with oppositely arranged slots, as 104, and onto said tapered portion is threaded the nut 105. From the foregoing it will be understood that the vertically movable feed frame is yieldingly and adjustably held in its elevated position subject to manual control.

There is herein employed, as in the construction represented by the patent previously referred to, a fabric bender the construction and control of which will now be explained. 106 represents a horizontally arranged rock-shaft mounted in suitable bearings formed in the frame 1 and carrying a rock-lever 107, one end of which is forked to embrace an eccentric 108 carried by the reduced portion 19 of the feed-shaft 18, the opposite end of said rock-lever being divided and provided with oppositely arranged bearings in which is trunnioned a short shaft 109, and through the latter loosely passes a standard 110 suitably secured at its lower end in a short rock-shaft 111 carried by the fabric-bender rock-lever 112, the latter suitably secured upon a rock-shaft 113 journaled in suitable bearings formed in the frame 1. In the forward end of the rock-lever 112 is suitably secured a pin 114 whose free end loosely enters an opening 115 (shown in dotted lines only) in the fabric-bender 116 which latter extends upward past the rear side of the yoke 75, and through an elongated opening 117 in the feed-dog 70, which opening secures 130

said bender against movement in directions transverse to the length of the feed-dog, the upper end of the bender being housed in the opening 118 formed in the throat-plate 61, 5 which opening secures it against movements in the direction of the length of said feed-dog. The standard 110 is threaded at its upper end to receive an adjusting nut 119 provided with a slightly tapered threaded 10 portion 120 upon which is threaded a securing nut 121, the nut 119 being provided with a depending portion 122, and upon said standard is mounted a spring 123 seated at its lower end on a hub 124 forming a part 15 of said standard, the opposite end of said spring contacting with the inner end wall 125 of a tubular bushing 126 whose upper reduced end 127 abuts the short shaft 109. From the foregoing it will be understood 20 that the vertically movable fabric bender is yieldingly and adjustably held in its elevated position subject to manual control.

128 represents the needle-thread take-up cam mounted on and to rotate with the 25 main-shaft 2, said cam being provided with a groove 129 into which tracks a follower 130 carried by a short arm 131 of a two-armed lever 132 journaled on a stud-bolt 133 whose threaded end 133' passes freely 30 through the frame 1 and extends above the frame boss 133" to receive an internally threaded bearing stud, later to be referred to, the oppositely arranged arm 134 (shown in dotted lines only) of said lever carrying 35 the take-up arm 135.

The cloth-presser mechanism comprises a cloth-presser carrier 136 threaded at its upper end and at its lower end provided with a cross-bar 137 carrying a swinging cloth- 40 presser 138, the latter being provided with up-turned lugs, as 139, through which pass pivot-screws, as 140, threaded into said cross-bar. The cloth-presser carrier 136 passes through a tubular upright 141 formed 45 integral with a horizontal arm 142 slidably mounted in a bearing 143 formed in the lug 144 forming a part of the cylinder 5, a spring 145, (shown in dotted lines only) acting to hold the cloth-presser down upon 50 the fabric, the nut 145' threaded upon the upper end of the cloth-presser carrier acting to determine the vertical relationship of the cloth-presser with respect to the throat-plate 61 when the cylinder 5 is oscillated to its position to form stitches out of the fabric. The horizontal arm 142 is free to oscillate 55 in the bearing 143 and to be moved endwise in opposition to the resiliency of the spring 146 mounted on the arm 142 and held confined between a shoulder 147 and the inner 60 end of the nut 148 threaded upon the arm 142, thus permitting rocking movements of the cloth-presser in the direction of and transverse to the line of seam-formation. 65 148' represents a rib or ridge formed on

the under side of the cloth-presser which acts on the fabric to, in opposition to the throat-plate and close to the line of vertical movement of the fabric-bender while the fabric is being acted on by the latter and by 70 the needle to pierce the fabric, hold the latter from slight movement in the direction of the piercing movements of said needle to prevent any tendency of the fabric moving in such direction, and to prevent any tendency of the sewing operation to draw or 75 pucker the fabric in the line of seam-formation.

A needle-thread (not shown) is passed from the supply through a thread-check 80 149, thread-tension 150, thread leaders 151, 152 and 153, the latter carried by the needle-thread take-up, through a suitable opening in the needle-bracket 8 and from the latter to and through the eye of the needle, the 85 elements 149, 150 and 151 being carried by the frame plate 151'.

155 represents a spring depressed needle-guard mounted to move vertically in a suitable opening (not shown) in the vertical 90 portion 156 of the tubular portion 141 and controlled in its movements, relatively to the movement of the needle, by a two-armed lever 157 acted on by a suitable concaved surface (not shown) formed in the needle-bar, said needle-guard and means for controlling its movements being common to the construction represented by Patent No. 1,133,572 previously referred to.

Referring now to the upper feeding 100 mechanism, reference being had more particularly to Fig. 7, 158 represents a feed-cam carried by the feed-actuating shaft 18, 159 a feed rock-bar pivotally mounted on the stud-bolt 160 threaded into the frame 1. The 105 rear end of the rock-bar 159 carries a roller 161 which tracks a cam-groove 162 in said feed-cam, the opposite end of said rock-bar being pivotally connected with the feed-dog carrying bar 163 to which is secured by 110 screws, as 164, the shank 165 of the feed-dog 166, thus transmitting from said feed-cam feed movements to the feed-dog.

167 represents the feed-lift cam carried by the feed actuating shaft 18 and provided 115 with a cam-groove 167'. 168 the feed lift rock-bar provided with a cam-roller 168' tracking said cam-groove and with an upwardly extended bearing 169 journaled on an internally threaded bearing 169' threaded 120 on the upper end of the stud-bolt 133, the forward end of said feed-lift rock-bar being provided with an internal bearing 170 into which is journaled one arm 171 of a two-armed connection whose other arm 172 is 125 journaled in a bearing 173 in a bellcrank-lever 174 pivoted on a stud 175 threaded into a bracket 176 secured by screws, as 177, upon the frame 1, the arm 178 of the bellcrank-lever 174 being provided with a tubu- 130

jar bearing 179 into which is journaled a short arm 180 threaded to receive the nut 181 for securing the latter against endwise movement, said short arm forming a part 5 of a tubular rock-arm 182 in which is mounted to move vertically, in opposition to the spring 183, a feed-lift connection 184 whose lower end is hinged to the feed-dog shank 185 by pivot screw 185, a nut 186 threaded 10 upon the upper end of said connection acting to adjust the degree of pressure exerted on the fabric by the feed-dog 166. 187 denotes a thread-guard carried by the swinging cloth-presser 138 and arranged between 15 the line of needle actuation and the limit of movement of said feed-dog in the direction of said needle to protect the needle-thread from being engaged by said feed-dog at such time as the latter is being moved downward 20 to engage the fabric to commence its feed movement. From the foregoing descriptive matter relating to both the upper and under feeding mechanism, it will be readily understood that the feed movements of the feed-dogs are effected simultaneously, the object 25 being to insure that each superposed ply of fabric will be given the same amplitude of feed movement, which result cannot be relied upon when only a single feeding mechanism 30 is employed.

When it is desired to employ the present construction for stitching a continuous seam comprising oppositely directed seam formations, as when stitching the stiffening to a 35 fabric comprising the collars or lapels of coats or cloaks, the effective action of the upper feeding-mechanism must be dispensed with, and to do this there is secured upon the frame 1, by pivot pin 188 secured in said 40 frame and adjusting screw 189 threaded into the latter a bracket 190 comprising a base portion 191 provided with a slot 192 and an arm 193 provided with an opening 194, the lower wall of the latter movable into and 45 out of supporting relationship with a pin 195 carried by a feed-dog supporting connection 196 hinged at its lower end on the pivot screw 185, so that when it is desired to employ the upper feeding-mechanism the 50 bracket 190 is oscillated on its pivot pin 188 to carry the lower wall of the opening 194 out of engagement with the pin 195 and secured against accidental movement by the screw 189, but when it is desired to annul 55 the effective action of the feed-dog, the latter is manually raised, the screw 189 loosened and the lower wall of the opening 194 moved into engagement with the pin 195, thus causing the feed-dog to be moved in a plane 60 above the fabric, and during such time the tubular rock-arm 182 partakes of its regular movements on the feed-lift connection 184, in opposition to the resiliency of the spring 183. 197 denotes a guide-pin carried by the 65 rock-arm 182, said pin tracking the forked

end of the connection 196 to hold the latter in vertical alinement with the arm 182 when the lower wall of the opening 194 is out of engagement with the pin 195.

The operation of the machine is as follows:—The operator, through a suitable treadle connection, rocks the lever 31 upward thus placing the vertically movable feed-frame and fabric-bender 116 in their depressed positions and introduces the fabric above the throat-plate 61 in position to be stitched when the operator permits the feed-frame and fabric-bender to take their normal positions, and the stitching operation is commenced. The fabric-bender is 70 moved in one direction during the formation of a given stitch and in an opposite direction during the next subsequent stitch, its upward movement into contact with the fabric occurring just before the point of the needle 75 enters the fabric to form the stitch in the fabric, thus serving to firmly hold the fabric in the opening 198 in the presser-foot. When the needle has entered the fabric the fabric-bender recedes so as not to influence the 80 movement of the needle while advancing to present the needle-thread loop to the action of the loop-taker, and as the needle recedes from the fabric the resiliently held feed-frame and presser-foot follow the upward 85 oscillation of the loop-taker and needle until the cloth-presser is clear of the fabric, and at such time the feed-frame is held against further upward movement by the nut 102 contacting with the tubular bushing 101 when the upward oscillation of the needle and loop-taker is continued to the position for forming the stitch located out of the fabric, and during the formation of the latter stitch the fabric-bender occupies its 90 depressed position, leaving the fabric free to be advanced under the needle but firmly held down upon the throat-plate by the 95 spring depressed cloth-presser 138.

Without referring further to the operation and control of the upper feeding-mechanism it is evident to those versed in the art that the effective action of such mechanism may be employed at the will of the operator, as the nature of the product may require, 100 and that the effective action of the feed-dog being directly upon the finished seam the pull action of said feed member effects a uniform pull action on the unsecured plies of fabric, thus insuring that the separate plies 105 will be advanced to the action of the needle without danger of their accidental disarrangement with respect to the line of seam-formation.*

Having thus set forth the nature of the invention, what I claim herein is:—

1. In a sewing machine, the combination with a stitch-forming mechanism including a needle, a needle carrying bar and means for operating said mechanism, of means for 110

- presenting the fabric to the action of said stitch-forming mechanism including a fabric bender, an under feeding mechanism comprising a feeding member having feed movements intersecting the path of needle movement, and an upper feeding mechanism including a feeding member co-operating with said under feeding member at the seam-finished side of the needle only.
10. 2. In a sewing machine, the combination with a stitch-forming mechanism including a needle, a needle-carrying bar and means for operating said mechanism, of means for presenting the fabric to the action of said 5 stitch-forming mechanism including a fabric-bender, an under feeding mechanism comprising a feeding member having feed movements intersecting the path of needle movement, and an upper feeding mechanism 15 including a feeding member extending across the finished seam and co-operating with said under feeding member at the seam-finished side of the needle only.
15. 3. In a sewing machine, the combination with a support for the fabric, means for holding the fabric down upon said support including a cloth-presser, a stitch-forming mechanism including a needle whose movements are controlled to pierce and emerge 20 from the same side of the fabric, upper and under feed-dogs and means for giving to said feed-dogs feed-movements, of a thread-guard carried by said cloth-presser and acting to protect the needle-thread from being 25 engaged by said upper feed-dog in its movements to feed the fabric.
20. 4. In a sewing machine, the combination with a support for the fabric, means for holding the fabric down upon said support including a cloth-presser, a stitch-forming mechanism including a needle, means for controlling the movements of said needle to pierce and emerge from the same side of the fabric including a fabric-bender and 25 means for advancing the fabric to the action of said stitch-forming mechanism, of means for securing the fabric against accidental movement in the direction of the fabric piercing movements of said needle including 30 a rib depending from the lower side of said cloth-presser.
25. 5. In a sewing machine, the combination with a stitch-forming mechanism including a needle, means for controlling the movements of said needle to pierce and emerge from the same side of the fabric, upper and under feed-dogs and means for giving to said feed-dogs feed-movements, of means for reversing 35 the feed-movements of said under feed-dog and means for suspending the effective action of said upper feed-dog to accommodate the reverse feed-movement of said under feed-dog.
30. 6. In a sewing machine, the combination with stitch-forming and cloth-feeding 40 mechanisms, the latter including a feed-dog located below the fabric, of means for transmitting from the actuating mechanism of the sewing machine feed movements to said feed-dog in one or in the opposite direction 70 including a feed-shaft provided with a driven gear-member, a feed reversing shaft provided with multiple driving gear-members in constant mesh with said driven gear-member and means, manually controlled, 75 for effecting and discontinuing power transmission between either the one or the other of said driving gear members and said driven gear member for transmitting to the feed-actuating shaft movements in one or in the opposite direction, dependent upon the character of the product being acted on.
35. 7. In a sewing machine, the combination with stitch-forming and cloth-feeding mechanism, the latter including a feed-dog located below the fabric, of means for transmitting from the actuating mechanism of the sewing machine feed movements to said feed-dog in one or in the opposite direction 80 including a feed-shaft provided with a driven gear member, a feed reversing shaft provided with multiple driving gear-members in constant mesh with said driven gear-member and a slidably mounted switch, the latter 85 manually controlled to effect or to discontinue power transmission between either the one or the other of said driving gear members and said driven gear member for transmitting to the feed-actuating shaft movements in one or in the opposite direction, 90 dependent upon the character of the product being acted on.
40. 8. In a sewing machine, the combination with a stitch-forming and cloth-feeding mechanism including a vertically movable feed-frame located below the fabric and normally in engagement with a cloth-presser located above the fabric, of means for transmitting from the actuating mechanism of the sewing machine feed movements to said feed-dog in one or in the opposite direction 95 including a feed reversing shaft, a feed-shaft provided with double eccentrics housed in said frame, and manually controlled means for moving said frame out of engagement with said cloth-presser to make convenient the placing of the fabric in position to be acted on by said stitch-forming and cloth-feeding mechanism.
45. 9. In a sewing machine, the combination with a stitch-forming and cloth-feeding mechanism including a vertically movable feed-frame located below the fabric and normally in engagement with a cloth-presser located above the fabric, of means for transmitting from the actuating mechanism of the sewing machine feed movements to said feed-dog in one or in the opposite direction 105 including a feed reversing shaft, a feed-shaft provided with double eccentrics housed in said frame, and manually controlled means for moving said frame out of engagement with said cloth-presser to make convenient the placing of the fabric in position to be acted on by said stitch-forming and cloth-feeding mechanism.
50. 10. In a sewing machine, the combination with a stitch-forming and cloth-feeding mechanism including a vertically movable feed-frame located below the fabric and normally in engagement with a cloth-presser located above the fabric, of means for transmitting from the actuating mechanism of the sewing machine feed movements to said feed-dog in one or in the opposite direction 110 including a feed reversing shaft, a feed-shaft provided with double eccentrics housed in said frame, and manually controlled means for moving said frame out of engagement with said cloth-presser to make convenient the placing of the fabric in position to be acted on by said stitch-forming and cloth-feeding mechanism.
55. 11. In a sewing machine, the combination with a stitch-forming and cloth-feeding mechanism including a vertically movable feed-frame located below the fabric and normally in engagement with a cloth-presser located above the fabric, of means for transmitting from the actuating mechanism of the sewing machine feed movements to said feed-dog in one or in the opposite direction 115 including a feed reversing shaft, a feed-shaft provided with double eccentrics housed in said frame, and manually controlled means for moving said frame out of engagement with said cloth-presser to make convenient the placing of the fabric in position to be acted on by said stitch-forming and cloth-feeding mechanism.
60. 12. In a sewing machine, the combination with a stitch-forming and cloth-feeding mechanism including a vertically movable feed-frame located below the fabric and normally in engagement with a cloth-presser located above the fabric, of means for transmitting from the actuating mechanism of the sewing machine feed movements to said feed-dog in one or in the opposite direction 120 including a feed reversing shaft, a feed-shaft provided with double eccentrics housed in said frame, and manually controlled means for moving said frame out of engagement with said cloth-presser to make convenient the placing of the fabric in position to be acted on by said stitch-forming and cloth-feeding mechanism.
65. 13. In a sewing machine, the combination with a stitch-forming and cloth-feeding mechanism including a vertically movable feed-frame located below the fabric and normally in engagement with a cloth-presser located above the fabric, of means for transmitting from the actuating mechanism of the sewing machine feed movements to said feed-dog in one or in the opposite direction 125 including a feed reversing shaft, a feed-shaft provided with double eccentrics housed in said frame, and manually controlled means for moving said frame out of engagement with said cloth-presser to make convenient the placing of the fabric in position to be acted on by said stitch-forming and cloth-feeding mechanism.

housed in said frame, manually controlled means for moving said frame out of engagement with said cloth-presser to make convenient the placing of the fabric in position 5 to be acted upon by said stitch-forming and cloth-presser mechanism, and means for guiding in a right line the vertical movements of said frame.

In testimony whereof, I have signed my name to this specification, in the presence of 10 two subscribing witnesses.

DONALD NOBLE.

Witnesses:

STANLEY N. SMITH,
H. M. BURN.
